UNITED STATES PATENT OFFICE

152,921

DESIGN FOR A CABINET FOR A CLOTHES DRIER

Robert D. Shapter, Corry, Pa., assignor, by mesne assignments, to The Murray Corporation of America, a corporation of Delaware

Application August 16, 1947, Serial No. 140,922

Term of patent 7 years

(Cl. D49—1)

To all whom it may concern:

Be it known that I, Robert D. Shapter, a citizen of the United States, residing at Corry, in the county of Erie and State of Pennsylvania, have invented a new, original, and ornamental Design for a Cabinet for a Clothes Drier, of which the following is a specification, reference being had to the accompanying drawing, forming part thereof, and in which the figure is a front perspective view of a cabinet for a clothes drier, showing my new design, the opposite side of which is substantially like the side shown. The characteristic features of the design disclosed reside in the louvers on the lower portions of the cabinet having the configuration and arrangement shown.

I claim:

The ornamental design for a cabinet for a clothes drier, substantially as shown and described.

ROBERT D. SHAPTER.
